(57) **CLAIM**

The ornamental design for the dispensing portion of a dispenser, as shown and described.

DESCRIPTION

FIG. 1 shows a top, front perspective view of a dispensing portion of a dispenser showing my new design;

FIG. 2 shows a top plan view thereof;

FIG. 3 shows a front plan view thereof; the rear plan view would be a mirror image of the front plan view; and,

FIG. 4 is a left sided view thereof.
